UNITED STATES PATENT OFFICE.

WILLIAM O. BATT, OF WILMOT, KANSAS.

TRACK SUPPORTING AND FASTENING MEANS.

1,382,458.

Specification of Letters Patent. Patented June 21, 1921.

Application filed February 17, 1921. Serial No. 445,666.

To all whom it may concern:

Be it known that I, WILLIAM O. BATT, a citizen of the United States, and a resident of Wilmot, in the county of Cowley and State of Kansas, have invented a new and Improved Track Supporting and Fastening Means, of which the following is a description.

The general object of my invention is to provide an improved permanent track bed as well as track-fastening means in consonance with the novel bed, and means to buttress the track against spreading strains.

More specifically the invention has for an object to embody the invention in a form reflecting important practical considerations respecting strength and simplicity in the constructional elements employed and as regards the convenience of assemblage and installation.

Reference is to be had to the accompanying drawings forming a part of this specification, it being understood that the drawings are merely illustrative of practical examples of the invention.

Figure 1 is a transverse vertical section of track-supporting and fastening means embodying my invention;

Fig. 2 is a plan view thereof, the track bed being omitted;

Fig. 3 is a partly sectional side elevation of a modified form of the invention;

Fig. 4 is a transverse section of the construction shown in Fig. 3;

Fig. 5 is a perspective view showing a modification of the rail-fastening means for use at a rail joint;

Fig. 6 is a cross sectional view on a reduced scale and largely diagrammatic, the view being given to show a bed depressed between the stringers.

Referring at first more particularly to Figs. 1 and 2 the numeral 10 indicates the foundation of a concrete road bed having a finished layer 11 of finer material such as asphalt or the like. The bed is carried pronouncedly deeper at the sides, the concrete being laid in trenches as at 10^a. In connection with the road bed 10, 10^a, I employ precast stringers 12 of concrete or cement disposed above the trench fillings 10^a, on which stringers the track rails A are laid, the stringer sections in practice advantageously being cemented together or otherwise suitably joined (as indicated at 13, Fig. 3).

Transverse tie bars 14 are employed, disposed below the surface of the road bed and forming chairs 14^a adjacent to the ends thereof on which the stringers 12 are seated. Each stringer 14 outward of the chairs 14^a is formed with upstanding portions 15, the ends 16 of said tie bar being offset to extend laterally outward substantially above the plane of the body of the tie bar and in practice lying slightly below the tops of the stringers 12. Pre-cast concrete posts 17 are disposed in the road bed below the offset ends 16 of the tie bars and terminate preferably in a plane slightly above the under sides of the stringers 12. On top of the posts 17 a finer grade of cement blocks 18 are disposed and these are formed with depressions 18^a which receive grouting, concrete, or other suitable road bed material, on top of which is a layer 11^a of asphalt or the like, on which the offset ends 16 of the tie bars rest. Each tie bar is anchored centrally by a pin 20 passed through a pin hole in said tie bar and into the ground. Also anchoring pins 21 are employed passing downwardly through the offset ends 16, through the bed material 19 and through vertical pin holes formed in blocks 18 and posts 17. The arrangement is such that the posts 17 and the blocks 18 act to buttress the road bed to resist any spreading tendency of the stringers 12. Outside of the posts 17 the road bed may be banked up by broken stone 10^b or other material. The anchoring pins 21 are preferably locked by wedges 22 driven through openings 16^a in the offset ends 16 and into the asphalt 11^a and bed material 19, the said wedges being accommodated in lateral slots 21^a (Fig. 2) in the heads of the pins 21. If desired, set screws 23 may be employed having threaded engagement with upstanding lugs 24 on the ends 16 and bearing against the wedges 22 to prevent loosening of the latter. I provide clamp means associated with the tie bars 14 for fastening the rails A, as follows: Clamps 25 extend laterally at their upper portions to overlie the flanges of the rails A at the outer sides of the rails, the bodies 26 of said clamps being in the form of vertical plates lying between the upstanding portions 15 of the tie bars 14 and the outer sides of the stringers 12, so that said clamps are firmly braced against said upstanding portions 15. The clamps are secured by vertical bolts 27 passing through

the bodies 26 of the clamps and through the tie bars 14 adjacent to the stringer seats 14a. At the inner sides the rails are secured by clamps 28 overlying the flanges at the inner 5 sides of the rails, the vertical bodies 29 of said clamps being disposed against the inner sides of the stringers 12 and being secured by vertical bolts 30 passing through said bodies and through oblong slots 33 in the 10 tie bar 14. Screws 31 have threaded engagement with upstanding lugs 32 on the tie bar 14 and bear at their forward ends against the backs of the clamp plates 29 pressing the same firmly against the stringers 12 at 15 the inner sides thereof.

In the form shown in Figs. 3 and 4, the elements shown in Figs. 1 and 2 are employed and in addition I provide in the concrete road bed 10^e gutter-shaped or 20 U-shaped pre-cast concrete beams 34 having drain holes 35 in the bottom thereof. Said beams 34 range lengthwise of the track between adjacent posts 17 and therefore lie directly beneath the stringers 12 and the 25 seats 14^a. The concrete 10^e is laid in trenches and forms a bed for the beams 34, said concrete also filling said beams. In Fig. 3 I have shown the described rail fastenings including the clamps 25, 28 as employed between the rail joints and at a rail joint 30 employing an ordinary fishplate 36.

In Fig. 5 at the rail joint I have shown clamps 25^a, 28^a of a form to constitute angle irons as well as clamps for the bases of the 35 rails, said clamps having the body plates 26^a, 29^a secured by vertical bolts 27^a, 30^a.

In Fig. 6 the bed 10^e for the stringers 12 has the top surface 10^d depressed between the stringers. The other elements indicated 40 in Fig. 6 correspond with those described above and bear corresponding characters. It is to be understood that the depressed bed of Fig. 6 is in practice given an asphalt or other suitable finish and has any approved 45 outlets for carrying off the water collecting in the depressed bed.

I would state in conclusion that while the illustrated examples constitute practical embodiments of my invention, I do not limit 50 myself strictly to the mechanical details herein illustrated, since manifestly the same can be considerably varied without departure from the spirit of the invention as defined in the appended claims.

55 Having thus described my invention, I claim:—

1. In a railway, concrete rail-supporting stringers, transverse tie bars affording seats near their ends for said stringers, means to 60 clamp track rails to said stringers and clamp the stringers on said seats, said tie bars extending laterally beyond said stringers and seats and having their ends offset in a plane above said seats, pre-cast concrete posts set 65 in the roadbed beneath said offset ends to

support the latter, and forming buttresses to resist spreading of the stringers, and means to fasten said offset ends to said posts.

2. In a railway, a concrete roadbed, transverse tie bars disposed in said bed below the 70 surface thereof, stringers supported on said tie bars inward from the ends thereof, said tie bars having upstanding portions at the outer side of said stringers, buttress posts in the roadbed outside of said upstanding 75 portions, and means securing the stringers in position.

3. In a railway, a concrete roadbed, transverse tie bars disposed in said bed below the 80 surface thereof, stringers supported on said tie bars inward from the ends thereof, said tie bars having upstanding portions at the outer side of said stringers and the ends of the bars being offset laterally outward at the upper ends of the upstanding portions, 85 posts beneath said offset ends, means to secure said offset ends to the posts and anchor the posts to the bed, means to anchor the bodies of the bars between said stringers, and means securing the stringers to the tie 90 bars.

4. In a railway, a concrete roadbed, transverse tie bars disposed in said bed below the 95 surface thereof, stringers supported on said tie bars inward from the ends thereof, said tie bars having upstanding portions at the outer sides of said stringers, and the ends of the bars being offset laterally outward at the upper ends of said upstanding portions, and means securing the stringers to the tie 100 bars.

5. In a railway, transverse tie bars having ends offset above the bodies of the bars and affording stringer seats inward from 105 said ends and presenting upstanding portions between said seats and offset ends, and upstanding clamps on the bars at the sides of said seats and adapted to receive and secure stringers.

6. In a railway, transverse tie bars having ends offset above the bodies of the bars and affording stringer seats inward from 110 said ends and presenting upstanding portions between said seats and offset ends, and stringer-securing means disposed respectively adjacent to said upstanding portions and laterally inward therefrom to receive and secure stringers therebetween.

7. In a railway, transverse tie bars affording seats for rail-supporting means, clamps 120 resting on said tie bars at the sides of the seats adapted to receive the rail-supporting means therebetween, said clamps presenting members to engage the rails, and vertical bolts extending through said clamps and 125 adapted to secure the same to the tie bars.

8. In a railway, transverse tie bars affording seats for rail-supporting means, clamps resting on said tie bars at the sides of the 130 seats adapted to receive the rail-supporting

means therebetween, said clamps presenting members to engage the rails, and vertical bolts extending through said clamps and adapted to secure the same to the tie bars, 5 those clamps at the inner sides of the seats being laterally adjustable on the tie bars; together with horizontally disposed set screws operating in members of the tie bars and adapted to bear against said adjustable 10 clamps.

9. In a railway, transverse tie bars adapted to receive rail-supporting means inward from the ends of the bars, posts in the roadbed beneath the ends of the tie bars, and anchoring means securing said ends to said 15 posts.

10. In a railway, transverse tie bars adapted to receive rail-supporting means in-

ward from the ends of the bars, pre-cast concrete posts in the roadbed beneath the 20 ends of the bars, said posts presenting depressions at the top, filler means in said depressions beneath the ends of the tie bars, and means to anchor said ends to said posts.

11. In a railway, a concrete roadbed, 25 transverse tie bars in said concrete bed below the surface thereof and adapted to receive rail-supporting means inward from the ends of said bars, pre-cast posts beneath the ends of the bars, anchoring pins extending through the ends of the bars and into said 30 posts, and wedges to lock said anchoring pins, and means to prevent displacement of the wedges.

WILLIAM O. BATTS.
